Burnham & Stickney

UNITED STATES PATENT OFFICE.

BURNHAM C. STICKNEY, OF ELIZABETH, NEW JERSEY, ASSIGNEE TO UNDERWOOD COMPUTING MACHINE COMPANY, OF NEW YORK, N. Y., A CORPORATION OF NEW YORK.
COMBINED TYPE-WRITING AND COMPUTING MACHINE.

1,270,242.

Specification of Letters Patent. Patented June 18, 1918.

Application filed May 24, 1912. Serial No. 699,377.

To all whom it may concern:

Be it known that I, BURNHAM C. STICKNEY, a citizen of the United States, residing in Elizabeth, in the county of Union and State of New Jersey, have invented certain new and useful Improvements in Combined Type-Writing and Computing Machines, of which the following is a specification.

This invention relates to combined type-writing and computing machines of the class in which numeral keys are caused to set up computing pins on rack bars, a general operator being consequently employed to rotate the dial wheels simultaneously to various extents determined by said pins, and is an improvement on the construction disclosed in my Patent, No. 1,186,520, issued June 6, 1916.

In the patent above mentioned, I showed how machines of this general character could be simplified in structure, the parts, especially the computing or dial wheels, rendered more accessible, and the cost of producing the machine reduced by devising a mechanism enabling the placing of the pin-setting mechanism at one side of the typewriter frame and with the sets of dial wheels forming computing heads at the front and top of the typewriter frame. In the present improvement arrangement is made whereby a series of primary computing heads are arranged to travel, so as to come successively into coöperation with the pin-carrying rack bars so as to be rotated thereby to run up the numbers indexed by the setting up of the pins on the rack bars whereby a series of distinct columns can be added vertically and have their individual sums recorded on the separate computing heads. An accumulating or cross-adding computing head is also provided in which is run up the cross computation of the numbers comprising the several columns.

In carrying out this improvement a computing carriage may be provided to carry the series of computing heads, which may be moved by the typewriter carriage or as shown, by its own spring under the control of the typewriter carriage. The computing heads thus come successively and separately in register with the rack bars.

The pin rack bars are only brought into engagement with the individual vertical computing heads when a number is being run up by an actuation of the general op-

erator, so that the movement of the series of computing heads is not interfered with. When the rack bars, however, are brought into active engagement with a movement of the general operator, the accumulating computing head, which, in this instance, is shown to be non-traveling, is swung into driven relation with the particular primary computing head which happens to be in active relation with the pin bars so as to have its computing wheels rotated the same amount as the corresponding wheels of the primary computing head.

Other features and advantages will hereinafter appear.

In the accompanying drawings,

Figure 1 is a perspective view partly broken away to show the underlying structure.

Fig. 2 is a vertical section taken from front to rear.

Fig. 3 is a fragmentary front view in elevation, partly broken away to show the underlying structure, and showing all of the parts in their normal inactive positions.

Fig. 4 is a diagrammatic top plan view.

Fig. 5 is a fragmentary view partly in plan and partly in horizontal section, showing the connection of the numeral keys to the levers actuated thereby.

Fig. 6 is a detail vertical section taken from right to left, showing one of the denominational pin-bearing rack bars depressed in a position to have one of the pins thereon set by the associated linkage.

Fig. 7 is a view similar to Fig. 6, showing the parts in the same position as in Fig. 6 with the exception that one of the linkages has been raised to set the corresponding pin on the depressed column bar.

Fig. 8 is a fragmentary rear elevation, showing the transposing linkages, whereby the denominational column bars are offset from their fellows by means of tappets carried by the carriage.

Fig. 9 is a fragmentary top plan view, showing a portion of the means for controlling the movement of the computing carriage from the typewriter carriage.

Fig. 10 is a diagrammatic view, showing the relation of the accumulating computing head wheels to one of the primary computing head wheels, and also showing the arrangement of the tens-carrying mechanism for both.

Fig. 11 is a vertical detail section showing the general operator as having moved far enough on its forward stroke to bring the toe of the shifting bell crank out of the notch in the cam, so as to raise the pin-bearing rack bars into mesh with the associated pinions carried by the dial wheels, and also showing the toe of the other shifting lever raised out of the notch onto the major portion of the cam so as to swing the pinions of the accumulating or cross-adding computing head into mesh with the gears of the primary computing head so as to be driven thereby.

Fig. 12 is a vertical section on the line *a—a* of Fig. 15.

Fig. 13 is a view of the parts shown in Fig. 11, showing the general operator and the parts moved thereby in the act of starting on their return stroke after they have moved completely forward, so that the toes on both the shifting levers have slipped into the cam notches to cause the pin-bearing rack bars and the pinions of the cross-adding or accumulating computing head to move out of mesh with the associated gears carried by the dial wheels of the primary computing head which happens to be in action.

Fig. 14 is a view of the parts shown in Figs. 11 and 13, showing the parts in their relative relation at a point substantially midway between the ends of the return stroke of the general operator.

Fig. 15 is a vertical section taken at right angles to the views shown in Figs. 11, 13 and 14, and showing the clutch connection of the parts whereby the cam disks can rotate during the forward movement of the general operator and the associated mechanism and yet remain stationary during the return movement, and also showing the clutch connection whereby the tens-carrying assisting mechanism remains inactive during the forward stroke of the general operator and comes in play during the return stroke of the general operator.

Fig. 16 is a vertical section on the line *b—b* of Fig. 15.

Fig. 17 is a fragmentary view showing more clearly the relative arrangement of the lever for shifting the cross-adding or accumulating computing head, with respect to its actuating cam.

Fig. 18 is a fragmentary view in elevation showing a portion of the mechanism for controlling the movement of the computing carriage from the typewriter carriage.

Fig. 19 is a fragmentary front view in elevation, showing the series of primary computing heads at the right.

Alphabet keys 1 and numeral keys 2 depress levers 3, to rock bell cranks 4, which swing type-bars 5 to print upon a platen 6. The platen is mounted upon a carriage 7, which, as usual in the Underwood typewrit-

ing machine, is driven by a spring barrel 8. The step-by-step or letter-feeding movement of the carriage is controlled by dogs 9, which are operated by a universal bar 10, actuated by heels 11 on the type-bars.

The numeral key-levers 3 have pendent links 12, pivoted at their lower ends to levers 13 of the first order, fulcrumed at 14 upon fixed brackets 15. These levers extend toward the right of the keyboard, Fig. 5, and at their outer ends are pivoted to the bottom ends of upstanding links 16, to thrust the latter up as the keys descend. The links 16 may have returning springs 16^a, and may be in a row parallel with the key-levers at Fig. 5, and the levers 13 may be of assorted lengths; and the links 12 may be disposed in a diagonal row so as to give clearance; while the fulcrums 14 may be so placed that the thrust links 16 are given equal movements. It is obviously not essential to place the levers 13 diagonally; and it is also apparent that the numeral key levers 3 may be otherwise connected to the links 16.

These links 16 are connected at their upper ends with a set or nest of linkages intended to set up the computation pins. Each linkage comprises a horizontal pin-setting bar 17, to which the upper end of its link 16 is pivoted at 18, Fig. 6. This horizontal link 17 is pivoted at its ends upon a pair of bell cranks 19, 20, which are connected by a link 21, so that said link 17 is given a parallel movement up and down. When one of these links 17 is thrust up, it sets one of its computation pins 22 in the manner indicated at Fig. 7.

The computation pins are arranged in eight rows of nine pins each, one row being mounted upon each bar 23. The nine bars 23 carry at their forward ends racks 24, for communicating movement to nine dial wheels 25, arranged at the front of the machine about on a level with the typewriter carriage, where they may be easily read.

It will be seen that these computation racks or bars 23 are compactly mounted at one side of the frame of the typewriting machine, preferably at the right-hand side, and that the links 16, as well as the pin-setting linkages, are all compactly placed under the rack bars 23, and connected by simple devices to the keys; whereby great economy of room is effected, and the necessity of unduly elevating the keyboard of the machine is avoided.

When the computation racks 23 are in normal positions, they are out of reach of the pin-setting linkages 17; and provision is made whereby the typewriting carriage 7 depresses the computing racks or bars *seriatim*, so that the linkages may set the pins thereon.

From a rod 26, fixed or mounted on the carriage, extend rearwardly a pair of arms 27, carrying a rack 28, along which are in-

dependently adjustable several dogs 29, in position to engage, one after another, a series of rock-arms 30, which are loosely mounted upon a fixed shaft 31, and each connected by a bail 32 to a forwardly-extending arm 33, the latter having at its forward end a pin 34, engaging a horizontal slot 35 in a computation bar 23; the slot permitting the pin to raise or lower the rear end of the bar, without interfering with the longitudinal movement thereof which occurs at the operation of turning the computing wheels. The dog 29 may vibrate any arm 30 and bail 32, together with that arm 33 which is preferably integral with the bail 32 and arm 30, so that the pin-carrying bar is swung down to enable any of the linkages 17 to thrust up the overlying pin, see Figs. 6 and 7.

It will be seen at Fig. 8, which is a rear elevation, that the denominational order of the arms 30 is the reverse of the denominational order of the arms 33, all the bails being nested one within another as shown, to form a denomination-transposing device, so that while the operation of the arms 30 proceeds toward the right at Fig. 8, the operation of the arms 33 proceeds toward the left, at said figure, so that as the carriage proceeds in letter-feeding direction, the computation bars 23 will be depressed in the proper order beginning with the highest denomination, since it is the arm 30 of highest denomination which is first rocked by the carriage-dog 29.

From the foregoing, it will be seen that at the completion of a letter-feeding movement of the typewriter carriage, one of the pin-carrying racks is depressed, and that at the ensuing stroke of a numeral key a computation pin is lifted upon said rack or bar, so that said pin will project above its fellows when the bar is returned to its normal elevated position. In this manner, the pins are set up one after another, as the number is written upon the work sheet which is carried upon the platen. At the completion of the writing of the number, the operative pulls forwardly a handle 36 on an arm 37 which extends from a rock shaft 38. The latter also carries an upstanding arm 39, which forms part of the general operator of the computing mechanism, and the principal function of which is to rotate the dial wheels 25 as determined by the computation pins which have been set up by the keys 2.

At the initial part of the forward stroke of the general operator 39, the computation racks 24 are shifted up into mesh with pinions 40 fixed one to each of the dial wheels 25. It will be seen that the racks 24 preferably stand normally well below the dial wheels 25, to permit the latter to travel with the computing carriage upon which they are mounted, as will presently be explained.

This shifting of the racks 24 up into mesh with the pinions, is effected through the in-

strumentality of a horizontal driver 41, pivoted at its rear end at 42 to the upper end of arm 39, and extending forwardly and carrying on its forward end a rack 43, which meshes with an idle pinion 44, the latter 70 meshing with a pinion 45 on a shaft 73, which carries a rack-controlling disk 47, provided with a cam 48. This cam forms one side of a notch cut in said disk. This notch is normally occupied by a finger or toe 49, 75 carried upon an arm 50, which extends up from a rock shaft 51 mounted in the framework of the machine.

Forwardly from said rock shaft 51 extend two arms 52, united by a shifter bar 53, 80 which passes through horizontal slots 54 in all the racks 24, whereby said bar 23 may shift the racks up into mesh with the computation pinions 40, and down to normal position.

Sufficient rotation of the disk 47 is effected to cam the finger 49 out of the notch 48, and thereby lift the racks 24, before the latter advance longitudinally. The positions of the parts at this moment are seen at Fig. 11. 90

The racks 24 are now in mesh with the computation pinions 40, in which position they are held or locked by reason of the engagement of finger 49 with the cylindrical or unmodified periphery of the disk 47. A 95 horizontal cross-bar 55, forming part of the general operator, now advances to engage all of the computation pins 22 which have been set up by the keys 2, and to advance the computation racks accordingly during the 100 remainder of the forward stroke of the general operator arm 39; whereby the pinions 40 and dial wheels 25 are rotated accordingly, to add upon the dial wheels the number which has just been written upon the 105 work sheet.

The rack-advancing bar 55 is carried by a pair of arms 56, seen in plan at Fig. 4, which are fixed upon a rock shaft 42, carried in a fork 57 formed upon the upper end of the 110 general operator arm 39, Fig. 1; the driving bar or rack 41 aforesaid being loose on said rock shaft, and supported at its forward end on a guide roll 58 which is placed directly beneath pinion 44, Fig. 2. The rack-advancing bar 55 may rest directly upon the racks, and may be swiveled at 59 to its driving arms 56, to accommodate itself to the slight inclination of the rack bars as they rise into mesh with their pinions. A spring 115 60 may be provided upon the rock-shaft 42, to hold the bar 55 lightly down upon the racks.

The dial wheels 25 having thus been rotated, and the general operator having completed or substantially completed its forward stroke, the racks 24 are dropped out of mesh with the pinions, preparatory to beginning their return strokes to normal positions. This unmeshing is caused by the rack-con- 130

trolling finger 49 falling again into the notch in the cam disk 47; the other wall of said notch being designated as 61, and being abrupt, so that the racks may drop promptly 5 on the completion of the rotation of the notched disk 47 through a single revolution. It will be understood that the handle 36 is pulled down by the operative until it is arrested by an adjustable stop 62, after the 10 racks 24 have dropped; and that thereupon the operative lifts said handle and returns the general operator to normal position, ready for another computation. During such return stroke, the racks 24 ride backwardly upon the guides 34, 53, without turning any wheels. A spring 62^a may either effect or assist the return of the general operator.

During the return stroke of the general 20 operator, the cam disk 47 remains stationary, being held against rotation by the finger 49 which occupies the notch and serves as a 25 detent; a spring 63 (Fig. 3), coiled around the rock shaft 51, aiding the weight of the racks in maintaining said finger 49 against displacement.

The pinion 45, however, is also employed 30 for driving the tens-carrying trains; and for this purpose it makes a single revolution in reverse direction during the return stroke of the general operator. To permit this return stroke while cam disk 47 is stationary, a loose connection is provided between said pinion 45 and said disk 47, this connection 35 comprising a pawl or clutch 64, Fig. 13, which is pressed by a spring 65 into engagement with a single shoulder 66 formed on a clutch disk 67, which is fixed to the pinion 45 preferably by a pin 68, Fig. 15. The pinion 45 may, therefore, move in return or clockwise direction at Fig. 14, independently of the cam disk 47; but when said pinion is advancing or moving counterclockwise at said figure, it gives the cam disk 47 a complete revolution in the same direction, for the purpose already explained.

The rack-advancing bar 55, during the return motion of the general operator 39, engages lugs 69 formed on the computation 50 bars 23, and restores them to normal positions. The bar 55 may be undercut or beveled on its rear edge at 70, to enable it to ride over any pins 22 which may be accidentally set up while the general operator is in the 55 abnormal Fig. 13 position.

Upon each of the dial wheels 25 (except the wheel of highest denomination) is a tooth 71, to start the associated tens-carrying 60 train, which comprises a 9-tooth pinion 72 engageable by tooth 71 and rotated thereby through one-ninth of a revolution. The normal position of the tens-carrying train is seen at Fig. 10, while the position to which it is turned by tooth 71, is seen at Fig. 13.

Upon the shaft 73, which carries the driv-

ing pinion 45, are placed eight spurs or segments 74, which are rotated in clockwise direction at Fig. 10 by the pinion 45 during the return stroke of the general operator. If any of the tens-carrying trains have not 70 been started, the movements of their associated spurs will be idle, since every second tooth of the pinion 72 is cut away, as at 75, to give clearance for these driving spurs, and this clearance normally stands opposite to 75 the spur-shaft 73, as at Fig. 10. In case, however, any pinion 72 has been started, the ensuing movement of the associated spur 74 will rotate the pinion through two-ninths of a revolution; making one-third of a revolution 80 in all.

To each pinion 72 is fixed a three-toothed pinion 76, to turn into mesh with an advance for one-tenth of a revolution a ten-toothed gear 77, which is fixed to the dial wheel 25 85 of next higher denomination, thereby carrying 1 over to the last-mentioned dial wheel. The shaft 73 is motionless during the advance stroke of the general operator, because it has a clutch connection to the pinion 45, 90 (see Figs. 12 and 15). In a hub 78 mounted on the shaft, and connected to the pinion 45 by a sleeve 78^a, is a pocket 79 to receive a spring 80 and a ball 81, the latter being pressed into a recess 82 in a collar 82^a secured to the shaft 73 which carries the segments 74. A notched disk 83 is provided upon the spur-shaft 73, a spring detent 84 normally occupying the notch to hold the shaft and the spurs thereon in normal positions. 100

It will thus be seen that during the return stroke of the general operator, the carry-over trains are operated wherever necessary; this carry-over mechanism corresponding 105 generally with that disclosed in the application of Frederick A. Hart, No. 466,836, dated December 10, 1908.

During the final portion of the return stroke of the general operator, the computation pins 22 which were originally projected, are restored to normal positions by means of a plate 85, overlying the pins and fixed upon a pair of arms 86, which extend forwardly from a rock shaft 87 journaled in the framework, the latter comprising side plates 88, 89, between which said rock shaft extends, and which are fixed to the main frame of the typewriting machine at one side thereof. Rearwardly from said rock shaft extends an 110 arm 90, having at its rear end a bevel 91, which is engaged by a cam or tappet 92 on the fork 57 of the general operator arm 39; whereby the arm 90 is cammed up, and the plate 85 is swung down to depress all of the 115 projected pins 22 to their normal positions. 120

The cam or tappet 92 finally escapes from the cam 91, and a spring 93, Fig. 4, lifts the pin-restoring plate 85 to normal position, as at Fig. 2. During the forward 130

stroke of the general operator, the tappet 92 passes freely by the cam 91, the former being pivoted at 94 to the general operator arm, to permit it to yield. A spring 95 thereupon restores the tappet 92 to normal position, resting against a stop 96 on the general operator arm.

In the specific description so far given only one set of computing wheels to form 10 a computing head has been mentioned. In fact, however, as shown in this case, the computing wheels 25 are arranged in groups so as to form a series of primary computing heads 99. These computing 15 heads are mounted on a carriage 100 which, itself, is mounted in guideways 101 and 102 of any suitable character so that it can slide longitudinally to bring the several computing heads successively into coöperation with the nest of rack bars 23.

While the computing carriage 100 could be connected directly to the typewriter carriage 7 so as to be moved thereby, in this instance it is shown to be propelled by separate 25 rate means shown in the nature of a spring barrel 103 connected to the carriage 100 by a tape 104. On the stationary portion of the machine, such as the frame which supports the guides 101 and 102, there is pivotally 30 mounted a latch 105 which is adapted to engage successively each one of a series of lugs 106 located at intervals corresponding to the location of the several primary computing heads. This latch is held by a 35 spring 107 in its locking position so that it prevents the forward movement of the computing carriage 100 under the tension of its spring barrel 103.

The opposite end of the latch 105 is provided with a trip 108 which, during the 40 movement of the typewriter carriage 7 to the left, may be engaged successively by a series of tappets 109 adjustably mounted on a rod 110 at intervals from each other 45 corresponding to the intervals of the tappets 29 on the back of the carriage. When one of the tappets 109 comes in engagement with the trip 108 during a letter-feeding movement of the carriage 7, the latch 50 105 will be rocked against the tension of its spring 107 to release the lug 106 which happens to be in engagement with the end of the latch 105, permitting a jump movement of the computing carriage 100, the spring 107 55 returning the latch before the next lug comes into a position to be caught. This is made possible by having the movement of the latch 105 take place during a single letter space movement of the typewriter 60 carriage 7.

The trip 108 is pivotally mounted on the latch 105 in such a manner that while it forms a rigid intermediary when approached by one of the tappets 109 during 65 a letter-feeding movement of the carriage

7, it will yield when contacted during the return movement of the carriage so as to enable the tappets 109 to pass idly by. The return of the typewriter carriage 7 is utilized to return the computing carriage 70 100. For this purpose there is provided on the shaft 110 a finger 111 bent to avoid parts in the way, and extending forward so as to engage the left hand edge of the carriage 100.

It will be seen by this arrangement that a series of separate and individual vertical columns of numbers can be added up and their individual totals registered on the several computing heads 99. It is desirable in addition to these individual totals to obtain a gross total and to cross-add the columns so as to check the result obtained by the primary computing heads. For this purpose there is provided an accumulating 80 85 or cross-adding computing head 112. The accumulating computing head 112 is, in this instance, shown to be stationary in order that it may co-operate successively with each of the primary computing heads 99.

The computing head 112 is arranged so that it will be rotated by the computing wheels of the computing heads 99, so as to run up corresponding amounts on both computing heads concomitantly. It will be 90 seen that in view of the relative movement of the primary computing heads 99 and the accumulating computing head 112, it is necessary that they should move out of co-operation with each other so as to permit 100 of the relative longitudinal movement. In fact, as the invention is here illustrated, the accumulating computing head 112 is always out of co-operation with the primary computing head which happens to be in an 105 active position until such time as a computation is run up by an actuation of the general operator 39. For this purpose the computing head 112 has its computing wheels, indicated at 113, each of which comprises a 110 dial wheel 114 and a gear 115, mounted on a floating shaft 116 which is secured in a rocking frame 117. The rocking frame 117 has forwardly extending arms 118 provided with offset or angular front ends which 115 form means of support for a shaft 119 on which are mounted idler pinions 120 forming intermediaries between the gears 115 and the gears 77 carried by the computing wheels of the primary computing heads. 120

Normally the frame 117 which is pivotally mounted on the shaft 73 is held in such a position that the computing head 112 is out of co-operation with the opposite primary computing head 99 by means of a spring 121 (Fig. 17) which engages an arm 122 extending to the opposite side of the shaft 73. This arm 122, which forms a lever with the remaining portion of the rocking frame, is provided with a curved finger or toe 123 130

which normally engages in a notch or socket 124 provided in a cam disk 125. The cam disk 125 is secured to rotate with a gear 126 which meshes with a gear 127 loosely mounted on the sleeve 78* which is concentric with the shaft 73.

The gear 127 is provided with a hub 128 in which is located a socket 129 (see Fig. 16). The socket 129 holds a spring 130 which tends to press a ball 131 out of a cam groove 132 provided in the gear 45. The arrangement of the cam groove 132 is such that a forward movement of the general operator 39 will cause a rotation of gear 45, as indicated by the arrows in Fig. 11, which rotation will cause the said gear 45 to be connected by this clutch mechanism to the gear 127, which will, in turn rotate the gear 126, so that the cam disk 125 will be rotated at this time.

A rotation of the cam disk will force the toe 123 out onto the cylindrical surface of the cam disk, thereby rocking the accumulating computing head 112 from the position indicated in Fig. 13 to the position indicated in Fig. 11, causing it to coöperate with the apposite computing head 99. The ratio of the gearing is such that when the general operator has completed its forward movement, the notch 124 will once more have come into such a position that the spring 121 can draw the toe 123 of the rocking frame into the notch or socket, thereby raising the accumulating computing head 112 out of coöperative relation with respect to the apposite primary computing head.

The tens-carrying mechanism for the accumulating or cross-adding computing head 112 is similar to that for the primary computing heads, and is in part distinct from this tens-carrying mechanism, and in part common therewith.

Mounted on the rocking frame 117 so as to be at all times in touch with the computing wheels 113, there are provided for each of the computing wheels 113 mutilated gears 133, which will be engaged once in a tenth of a revolution of the associated computing wheel 113 by a special tens-carrying tooth 134, which will rotate the mutilated gear one-ninth of a revolution. The mutilated gear is arranged so that the mutilated teeth will be normally in opposition to the swinging segments or sectors 74 on the shaft 73. The partial rotation of one-ninth of a revolution will, however, bring one of the teeth of the mutilated gear into such a position that it will be engaged by a sector or segment 74 during the return motion of the general operator. This segment or sector will rotate the mutilated gear through two-ninths of a revolution making one-third of a revolution in all.

Secured to each mutilated gear is a three-toothed gear 135, which will thus be rotated

through one-third of a revolution and will, by the engagement with the gear 115 of the computing wheel of the next higher denomination, rotate this gear one-tenth of a revolution carrying the tens over from the lower computing wheel. The assisting segments act for both the primary computing heads and the accumulating computing head.

In the use of the device, one of the tappets 29 through the associated set of linkages successively depresses each of the pin-bearing column bars, so that when one of the numeral keys is struck, one of the pins on the depressed bar can be raised above its fellows by the key-controlled parallel linkage. A successive operation of several of the keys and a concomitant movement of the carriage will set up or index a number comprising a series of digits. The general operator is then actuated by a movement of the handle 36 or any other suitable means, so that it swings forward the rack bar 41 which rotates, through the intermediary of the gear 44, the gear 45. The gear 45 is connected so as to rotate concomitantly during the forward movement of the general operator both the cam disk 47 and the cam disk 125.

On the initial rotation the toes of both of the rocking arms 50 and 122 are forced out of the notches or sockets so that they ride on the cylindrical periphery of the cam disks, thereby concomitantly raising the racks 23 into mesh with the gear 44 and depressing the accumulating computing head 112, so as to bring the pinions 120 into driven relation with the gears 75. This all happens before the pin bars themselves are moved longitudinally so that the computing wheels of both the primary and accumulating computing heads will be in driven relation with the rack bars 23. As soon as this has occurred, the bar 55 will come into engagement with such of the pins 22 as have been set up above their fellows and will move the supporting rack bars forward amounts corresponding to the particular pins set up. This enables the numbers previously struck by the numeral keys to be accumulated on both the primary and the accumulating computing heads.

When the general operator has approached the end of its forward stroke, the cam disks 47 and 125 will have been rotated a complete revolution, so that the toes on the ends of the lever 50 and the rocking frame 117 will automatically drop into the notches or sockets of the cam disks, enabling the rack bars 23 to fall out of mesh with the associated computing wheels of the primary computing head, and also enabling the accumulating computing head to be withdrawn upwardly out of coöperation with the primary computing head in action.

During the return movement of the gen-

eral operator, the cam disks, by reason of their clutch connections which act only in one way, will remain idle, while the shaft 73 which remained idle during the forward 5 stroke of the general operator is now connected up by its clutch, so as to rotate to cause the segments or sectors 74 to assist in the tens-carrying operation at such points as have become necessary by the passing 10 from "9" to "0" on the corresponding dial wheel.

When the general operator has completely returned, the primary computing wheels are free from all external contact so that 15 the primary computing heads may have such longitudinal movement as is necessary to bring the next successive primary computing head into apposite relation with the racks 23 and the accumulating comput- 20 ing head 112. To do this it is merely necessary to depress the space key or any other key of the typewriting machine until one of the tappets 109 cams the latch 105 to such a position that it releases the lug 106 which 25 happens to be in engagement therewith, permitting the computing carriage 100 to spring forward under the traction of its spring barrel to such a position that the latch 105 engages the next lug 106 to lock 30 the computing carriage 100 in such position that the next successive computing head will be in register with both the racks 23 and the accumulating computing head 112. The numeral keys can then be struck as 35 before, set up or index a number, and the number carried up in the same manner on both the primary computing head in action and the accumulating computing head, by a reciprocating movement of the general 40 operator.

Variations may be resorted to within the scope of the invention, and portions of the improvements may be used without others.

Having thus described my invention, I 45 claim:

1. The combination with a plurality of computing heads each including a set or group of computing wheels, of mechanism for indexing the series of digits of a number, means for transferring such indexed numbers to said computing heads, said means including a series of racks individual to the several wheels of a set, means for causing a relative movement between said 50 racks and said computing heads to enable the several computing heads to be operated successively by said racks, an accumulating computing head, and means for bringing said accumulating head successively into 55 driving relation with each of said first-mentioned heads, so that the one can be driven from the other.

2. The combination, with a plurality of primary computing heads, each head in- 60 cluding a group of computing wheels, and

mechanism for bringing said heads one after another into active position; of mechanism for indexing the series of digits of a number to be computed; mechanism for transferring said indexed number to the 70 wheels of the then active computing head, said transferring mechanism including a set of racks, one individual to each wheel, normally out of coöperative engagement with said wheels; an accumulating com- 75 puting head normally out of coöperative engagement with the active primary computing head; and means for concomitantly bringing said accumulating computing head and said racks into coöperative engagement 80 with said active primary computing head, thereby to enable the racks to run up the indexed number in the active primary com- puting head, and the latter to run up the same number in the accumulating comput- 85 ing head.

3. The combination, with a plurality of primary computing heads, and mechanism for bringing them one after another into active position; of an accumulating comput- 90 ing head; means for running up a number, comprising a series of digits, all at once on the then active primary computing head; and means for bringing the accumulating computing head into driving engagement 95 with said active primary computing head so that the one will be driven from the other, to run up in said accumulating computing head an equivalent of the number run up in the active primary computing 100 head.

4. The combination with a computing carriage having a series of computing wheels thereon, each having a dial wheel and a pinion, of racks mounted out of mesh with said pinions and movable into mesh therewith, a stationary set of computing wheels having means to coöperate with said first mentioned computing wheels but being normally out of coöperation therewith, and mechanism for shifting said racks and said second-mentioned computing wheels into coöperative relation with said first-mentioned computing wheels.

5. The combination with a computing head comprising a plurality of computing wheels, of a second computing head normally out of coöperative relation with said first computing head, a series of rack bars for operating one of said computing heads, cam mechanism for shifting said rack bars from a normal inactive position to an active position, a floating frame for supporting one of said computing heads, cam mechanism for shifting said frame, and a general operator 115 for actuating said cam mechanisms.

6. The combination with a typewriter car- 120 rriage having a step-by-step letter feeding movement, of a computing carriage having a jump movement equivalent to an aggre- 130

gate number of said step-by-step movements of said typewriter carriage, a series of computing heads on said computing carriage brought individually into action by the jump 5 movements of said computing carriage, mechanism for running up all of the digits of a number to be computed on an active computing head at one time, and an accumulating computing head arranged to receive 10 its rotation from any active computing head.

7. The combination with a typewriter carriage, of a series of computing heads, means for actuating one of said computing heads 15 at a time, carriage-controlled means for governing the active computing head, a cross adding computing head independent of control by said carriage, and means for bringing about the driving relation of the cross- 20 adding computing head with each of the first-mentioned computing heads, so that the one can drive the other, to enable said cross-adding head to accumulate the calculations of all said first-mentioned computing 25 heads.

8. The combination with a computing head, of an accumulating computing head, a floating frame for supporting one of said computing heads, a cam for oscillating said 30 floating frame to bring said computing heads into co-operation with each other, so that the one may drive the other, a general operator, a gear rotated by said general operator, and a one-way clutch connection 35 between said gear and said cam, so that said cam will be rotated solely during one portion of the movement of said general operator.

9. The combination with a plurality of 40 computing heads, of a floating support for one of said computing heads arranged to bring about the active and inactive relation of said computing heads so that the one may or may not drive the other, mechanism for 45 driving one of said computing heads, a cam for bringing said mechanism into its active relation with said last-mentioned computing head, a cam for oscillating said frame, a general operator, and gearing between each 50 of said cams and said general operator having each a one-way clutch connection enabling said cams to be actuated solely during a portion of the movement of said general operator.

55 10. The combination with a plurality of computing heads, of a floating support for one of said computing heads arranged to bring about the active and inactive relation of said computing heads, so that the one 60 may or may not drive the other, mechanism for driving one of said computing heads, a cam for bringing said mechanism into its active relation with said last-mentioned computing head, a cam for oscillating said 65 frame, a general operator, gearing between

each of said cams and said general operator having each a one-way clutch connection enabling said cams to be actuated solely during a portion of the movement of said general operator; and tens carrying mechanism 70 for both of said computing heads having a certain part in common, said certain part being arranged to be driven from said general operator and having a one-way clutch connection thereto so as to be operable solely during a certain portion of the movement of said general operator. 75

11. The combination with a computing head comprising a series of computing wheels, of a series of drivers for running up numbers in said computing head, one individual to each of said wheels for rotating the same, a second computing head including a series of computing wheels arranged to be driven from the computing wheels of said first-mentioned computing head, so that the number run up in the first-mentioned head will also be run up at the same time in the second-mentioned head, said second-mentioned computing head and said drivers being normally out of driving relation with respect to said first-mentioned computing head, and means for concomitantly bringing about a driving relation between said first-mentioned computing head and both said drivers and said second-mentioned computing head. 90

12. The combination with a computing head, of a series of drivers, a second computing head located intermediate said first-mentioned computing head and said drivers and arranged to be driven from the latter and to drive the former, but being normally out of driving relation therewith, and means for effecting a concomitant approaching movement of said first-mentioned computing head and said drivers toward said second-mentioned computing head from opposite sides thereof, so as to afford a driving relation between said second-mentioned head and both said first-mentioned computing head and said drivers. 100

13. The combination with a computing head, of a series of drivers for running up numbers in said computing head, a second computing head arranged to be driven from said first-mentioned computing head, said second-mentioned computing head and said drivers being normally out of driving relation with said first-mentioned computing head, a general operator for actuating said drivers to drive both said computing heads, and means actuated by said general operator for bringing about a driving relation between said first-mentioned computing head and both said second-mentioned computing head and said drivers before said general operator gives a driving movement to said drivers. 110

14. The combination with a computing 120

head, moving to and from an active position, of a tens-carrying mechanism for said computing head including a rotary assisting tens-carrying shaft, and a frame for supporting said computing head and pivotally mounted on said shaft so as to maintain said computing head and said tens-carrying mechanism always in the same general relation with respect to said shaft.

16. The combination with actuating means operating in a relatively fixed zone, of actuated means operated on in a relatively fixed zone, a series of computing heads moving head by head intermediate said actuating means and said actuated means, so as to be positively operated by the former, and so as to positively operate the latter, and means for vibrating concomitantly both said actuating and said actuated means into engagement with each of said computing heads.

16. The combination with a set of coordinate drivers, of a driven mechanism including a series of computing wheels, a computing head, and means for jumping said computing head in between said set of drivers and said driven mechanism, so that all of the wheels of said computing head may be positively driven by said drivers, and so that all of the wheels of said driven mechanism may be positively driven by said computing head, said computing head transmitting the drive from said set of drivers to said driven mechanism.

17. The combination of a primary computing head; mechanism for indexing the series of digits of a number to be computed; mechanism for transferring the indexed number to the primary computing head, including a set of racks, one individual to each wheel of said head, normally out of co-operative engagement with said wheels; an accumulating computing head normally out of co-operative engagement with said primary computing head; and means for concomitantly bringing said accumulating computing head and said racks into co-operative engagement with said primary computing head, thereby to enable the racks to run up the indexed number in the primary computing head, and the latter to run up the same number in the accumulating computing head.

18. The combination, with a series of computing heads, a typewriter carriage, and means controlled by said carriage for bringing about the movement of said heads one after another into active position; of mechanism for running up a multi-digit number

all at once into the then active head; a cross-adding head independent of control by said carriage; and means for bringing about the driving relation of the cross-adding head with said active computing head, so that the latter can drive the former to enable said cross-adding head to have run up therein, concurrently with the active computing head, the same number that is run up in said active computing head.

19. The combination, with a series of computing heads, a typewriter carriage, and means controlled by said carriage for bringing about the movement of said heads one after another into active position; of mechanism for running up a multi-digit number all at once into the then active head; a general operator for actuating said running-up mechanism; a cross-adding head independent of control by said carriage; means actuated by said general operator for bringing about the driving relation of the cross-adding head with said active computing head, so that the latter can drive the former to enable said cross-adding head to have run up therein, concurrently with the active computing head, the same number that is run up in said active computing head.

20. In a computing machine, the combination with a primary computing head, of carrying members therefor initially settable by said computing head, a secondary computing head actuatable simultaneously with said primary computing head, carrying members therefor initially settable by said secondary computing head, and carrying assisting mechanism including gears common to all of said carrying members.

21. In a computing machine, the combination with a plurality of primary computing heads, of carrying members common to all of said heads and initially settable by any head, a cross-computing head actuatable simultaneously with any primary computing head, carrying members initially settable by said cross-computing head when said head is actuated by any one of said primary computing heads, and carrying assisting mechanism including gears common to all of said carrying members, each of said gears acting to completely operate its associated carrying member common to the primary computing heads and also its associated carrying member of the cross-computing head.

BURNHAM C. STICKNEY.
